TION OF DELAWARE

SELECTOR SWITCH

Application filed February 14, 1927, Serial No. 167,908. Renewed January 14, 1929.

The present invention relates to new and improved selector switches for use in telephone systems, but is concerned more particularly with selector switches of the so-called 5 two-wire type in which at least one of the slow-acting control relays is shunted to secure its deenergization.

The broad general object of the invention is the production of a new and improved selector circuit in which the change-over relay 10 may be operated either in series with the primary operating magnet or in multiple with the said magnet, and whereby the position and manner of connecting of the change-over 15 relay may be varied according to the specific characteristics desired in any given instance.

Referring now to the drawings comprising Figs. 1-3, which show by means of the usual circuit diagrams three selectors embodying 20 the features of the invention, Fig. 1 shows a selector containing the usual line, release, change-over, stepping, and switching relays. In this drawing the relay C¹ is the series change-over relay, and arrangements are provided for connecting this relay in the operating circuit of the switch at any one of several points depending upon the requirements. 25

Fig. 2 shows a similar selector in which the change-over relay is arranged to operate in a 30 circuit independent of the operating and release magnets, being of the shunted type.

Fig. 3 shows a similar selector in which the change-over relay has its main winding connected in parallel with the primary operating magnet and in which an auxiliary winding is provided for reoperating the change-over relay during the releasing operation. 35

As regards certain features, this application may be considered an improvement on 40 the following copending applications:

Serial No.	Filing date	Inventor
64,301	Oct. 23, 1925	John I. Bellamy.
582,333	Aug. 17, 1922	Rudolph F. Stehlík.
710,577	May 29, 1924	Rudolph F. Stehlík.
744,119	Oct. 17, 1924	Rudolph F. Stehlík.

Referring now to the selector shown in Fig. 1, this selector has a line relay A¹ normally bridged across the incoming conduc-

tors 11 and 31. The relay B¹ is the release relay, and it is arranged to ground the release trunk conductor 21 so as to guard the associated trunk line from seizure and to maintain operated any previous switches. This 55 relay is used also to shift the operating circuit from the vertical magnet to the release magnet. The relay C¹ is the change-over relay and it is used primarily to initiate the rotary trunk hunting movement at the end of 60 the vertical group-selecting movement. Relay D¹ is the usual stepping relay and it is arranged to control the stepping action of the rotary magnet RO¹. Relay E¹ is the switching relay and it operates to switch the connection through to a seized trunk line when an 65 idle trunk line is found. The magnets V¹, RO¹, and RL¹ are the vertical, rotary, and release magnets, respectively. It will be 70 noted that terminals 2, 3, 4, and 5 are provided at various points in the operating circuits. These terminals are connected together by jumpers in the manner shown with the exception of one pair, and this pair of terminals is 75 connected by the jumpers 7' with the terminals 6 of the change-over relay C¹. When desired, the relay C¹ may be shifted to another portion of the circuit for purposes which will become apparent upon a further 80 perusal of the specification.

The operation of the selector shown in Fig. 1, with relay C¹ connected as shown, will now be explained.

When the selector is seized over the conductors 11, 21, and 31, a circuit is closed over conductors 11 and 31, in series for line relay A¹. Relay A¹ operates and closes a circuit for relay B¹ and magnet V¹ in series. It will be noted that, while all three contacts of the line relay are together, a circuit for C¹ and V¹ is established independent of relay B¹, but the duration of this circuit is only momentary and magnet V¹ and relay C¹ do not have time to operate before the circuit is 85 opened upon the completion of the stroke of relay A¹. Relay B¹ operates in series with magnet V¹, but the magnet does not operate on account of the relatively high resistance 90 of the relay. At its upper armature, relay B¹ places a ground potential on the release 95 100

trunk conductor 21 for guarding and holding purposes. At its lower armature, relay B¹ opens a point in the circuit of release magnet RL¹ and closes a locking circuit for itself, thereby preparing an operating circuit for relay C¹ and magnet V¹. At its inner lower armature, relay B¹ prepares a circuit for magnet RO¹.

Subsequent to the seizure of the selector, 10 a series of interruptions is produced in the circuit of the line relay by the calling device at the calling substation. Each time the circuit is interrupted, relay A¹ falls back and opens the initial circuit of relay B¹, at the 15 same time completing a circuit for vertical magnet V¹ and change-over relay C¹ in series through normal contacts of A¹, operated contacts of B¹, and normal contacts of E¹. Magnet V¹ operates each time this circuit is closed 20 and restores each time the circuit is opened. Relay C¹ operates upon the first closure of the circuit, but being slow-acting due to the copper sleeve placed on its core, it remains operated throughout the series of impulses. By 25 the operation of the vertical magnet V¹, the wipers of the switch (shown to the right of relay E¹) are raised step-by-step until they come to rest opposite the desired level of contacts, only one contact set being shown (to 30 the right of the wipers). Although the low-wound relay C¹ is connected in shunt of relay B¹ each time relay A¹ falls back, relay B¹ does not fall back due to self-induced circulating current.

35 Relay C¹, upon operating, short circuits relay E¹, preparing a circuit for relay D¹, which circuit is completed through the interrupter contacts of magnet RO¹ as soon as the associated off-normal contacts close, which 40 they do upon the first upward movement of the switch. When relay D¹ operates, it locks itself to the grounded release trunk conductor 21 at its inner armature, and prepares a circuit for rotary magnet RO¹ at its outer armature.

45 When relay C¹ falls back shortly after the termination of the series of impulses, it opens the initial circuit of relay D¹, leaving relay D¹ locked to conductor 21. At the same time, 50 the circuit of magnet RO¹ is completed through normal contacts of C¹, and operated contacts of B¹ and D¹. Upon operating in this circuit, magnet RO¹ advances the wipers one step into engagement with the first set 55 of bank contacts in the selected level. Near the end of its stroke, magnet RO¹ opens the circuit of stepping relay D¹, whereupon relay D¹ falls back and opens the circuit of the rotary magnet and opens a further point in its 60 own locking circuit. Rotary magnet RO¹ thereupon falls back and again closes its interrupter contacts.

65 If the trunk line connected to the first set of bank contacts is busy, a ground potential is encountered on the test contact by the test

wiper, and a circuit is closed through normal contacts of relays E¹ and C¹ and through the rotary-interrupter and off-normal contacts for reoperating the stepping relay D¹. Relay D¹ again locks itself to the release trunk conductor 70 75 80 85 90 95 100 105 110 115 120 125 130 conductor 21 and again closes the rotary magnet circuit, whereupon the wipers are advanced another step.

The alternate operation of the stepping relay and the rotary magnet continues until an idle trunk line is reached, whereupon the rotary movement stops because the stepping relay does not again operate. At this time, relay E¹, which has previously been short circuited continuously, in a circuit from the grounded release trunk conductor 21 and including the relay D¹ and the associated interrupter and off-normal contacts. Relay D¹ does not operate in this circuit because of the relatively high resistance of relay E¹. Upon operating, relay E¹ at its inner upper armature disconnects the test wiper from the test circuit and connects it to the grounded release trunk conductor 21, thereby making the seized trunk busy immediately. At its inner lower armature, relay E¹ disconnects ground from the lower armature of relay D¹ so as to prevent further operation of the vertical magnet V¹ and the change-over relay C¹ and to prevent a premature releasing operation when relay B¹ subsequently falls back. At its upper and lower armatures, relay E¹ disconnects relay A¹ from across conductors 11 and 31 and connects the said conductors to the corresponding wipers. Line relay A¹ falls back responsive to this operation, but the vertical magnet is not reoperated at this time because relay E¹ is operated. The initial circuit of relay B¹ is opened by line relay A¹, but relay B¹ does not fall back immediately because it is shunted through relay C¹ prior to the opening of its initial circuit. The result is that relay B¹ remains operated for an interval due to the self-induced circulating current, after which it falls back.

110 The usual relay action takes place in the seized trunk line, with the result that a ground potential is placed on the release trunk conductor thereof so as to maintain the connection established after relay B¹ falls back as 115 above described.

When the receiver is replaced at the calling substation, the ground potential is removed from the release trunk conductor of the established connection, whereupon relay E¹ falls 120 back and reconnects the test wiper to the test circuit, at the same time closing the release magnet circuit through normal contacts of relay B² and the associated off-normal contacts of the switch. Relay D¹ is reoperated in 125 case the test wiper encounters busy test contacts in releasing. This, however, does not result in a closure of the rotary magnet circuit on account of the fact that the rotary magnet circuit includes open contacts of the 130

relay B^1 . When the normal position is reached, the release magnet circuit is opened at the associated off-normal contacts.

It will now be assumed that a selector is desired having different characteristics, and that these characteristics can be met by including the series relay C^1 in a circuit between the terminals 3 instead of between the terminals 2. In this case, the jumpers 7' are removed from terminals 2 and are transferred to terminals 3, and the jumper shown between terminals 3 is moved to terminals 2. In this case, when relay A^1 operates upon the seizure of the switch, relay B^1 energizes in series with relay C^1 , but relay C^1 and the operating magnet are not operatively energized. As soon as relay B^1 operates relay C^1 is short circuited because ground potential is applied to both terminals. Each time relay A^1 falls back, relay C^1 is placed in multiple with relay B^1 , whereupon magnet V^1 operates, relay C^1 operating upon the first impulse and remaining operated throughout the series of impulses. Relay C^1 is short circuited again each time relay A^1 operates, being at the same time removed from in shunt of relay B^1 . When relay C^1 is used in this position, it is not essential that a copper sleeve be employed on the relay, as it is then slow-acting due to being short circuited when removed from the main circuit.

If it is found more convenient, relay C^1 may be inserted between the terminals four instead of between the terminals three, with much the same effect. There is one difference that may be pointed out. The shunt placed around relay B^1 upon the falling back of relay A^1 does not include a relay winding. There is a possibility that a selector may become mechanically defective so that it does not release when it otherwise would. For this reason, it is often desirable to prevent a selector from being seized for use in another connection until it has reached its normal position. If this action is desired, relay C^1 is connected into the circuit at the terminals 5 instead of at any of the other terminals. In this case, the relay C^1 is in the circuit of magnet V^1 as before, and it is also in the circuit of magnet RL^1 during the releasing operation. When relay C^1 reoperates during release, it recloses the circuit of relay D^1 , whereupon relay D^1 extends a ground potential to conductor 21, thereby guarding the switch against seizure. When the switch reaches its normal position, the associated off-normal contacts open the circuit of D^1 , whereupon D^1 falls back and removes the guarding potential. As the release magnet circuit is opened at this time, relay C^1 falls back and opens a further point in the circuit of relay D^1 . In this position of relay C^1 the copper sleeve is not required to make it slow acting, as C^1 is short circuited dur-

ing impulsing when it is not in series with magnet V^1 .

Referring now to Fig. 2, this modification will be described. It will be noted that the selector shown in Fig. 2 is substantially the same as that shown in Fig. 1 except that relay C^2 is a multiple relay instead of a series relay as is the corresponding relay in Fig. 1. Upon the seizure of the selector, relays A^2 and B^2 operate in the described manner, whereupon relay B^2 closes a locking circuit for itself at its lower armature. Each time relay A^2 falls back a circuit is closed at the lower normal contacts of relay A^2 for vertical magnet V^2 . A circuit is also closed each time relay A^2 falls back at the upper normal contacts for relay C^2 . Each time the relay A^2 reoperates, the vertical magnet V^2 falls back, but the change-over relay C^2 remains operated during impulsing on account of the fact that its winding is shunted by the associated resistance which allows a self induced circulatory current to be set up through the winding and resistance in series to maintain the relay operated for an interval after the last impulse.

Referring now to Fig. 3, the selector shown in this drawing is similar generally to the ones in Figs. 1 and 2, being more nearly like the selector in Fig. 2 in that a multiple change-over relay is used. Unlike the selector in Fig. 2, the selector in Fig. 3 contains a change-over relay connected directly in multiple with the vertical magnet at all times. When the line relay A^3 falls back after the selector has been prepared for operation by the energization of relay B^3 , a circuit is closed for the vertical magnet, and relay C^3 operates in multiple with it, but, when the line relay reoperates and removes the shunt from around relay C^3 , relay C^3 does not fall back, (although vertical magnet V^3 does). Instead, there is a self-induced circulatory current set up in relay C^3 which flows between battery and the junction of relay B^3 and magnet V^3 . This current joins the energizing current of relay B^3 , and shortly dies away. The circulatory current through relay C^3 does not have time to die away sufficiently to permit the relay to fall back during the vertical movement of the selector, but, when no further impulses are received after the end of the vertical movement, relay C^3 falls back, as it is adjusted so as not to hold up in multiple with the magnet V^3 when the two are in series with relay B^3 .

When the release of the selector occurs, relay C^3 reoperates, as its lower winding is in series with release magnet RL^3 . Relay C^3 guards the selector during the releasing operation. If this is not desired, the jumpers 9 connecting the lower winding of the relay with the terminals 8 may be omitted, in which case the terminals 8 are jumpered together.

It will be understood, of course, that, if desired, a second winding may be similarly placed on relay C², Fig. 2, and connected in a similar point in the release magnet circuit.

5. What is claimed is:

1. In an automatic selector switch containing a release relay and an operating magnet, a permanent connection between one terminal of the operating magnet and one pole of the exchange battery; a permanent connection between the other terminal of the magnet and one terminal of the release relay, normally-open contacts controlled by the release relay for closing a connection between 10 the other terminal of the release relay and the other pole of the exchange battery, and contacts controlled by the line relay for shunting the release relay to operate the magnet through the said contacts of the release relay.
2. In an automatic switch, a line relay, a release relay, an operating magnet, a connection between one pole of the exchange battery and one terminal of the operating magnet, a connection between the other terminal 25 of the operating magnet and one terminal of the release relay, means for closing a circuit path between the other pole of the exchange battery and the other terminal of said release relay to energize said release relay, contacts 30 on said release relay closed when the relay operates for closing another connection between the said other pole of the exchange battery and said other terminal of said relay, and contacts on the line relay closed when 35 the line relay is normal for shunting the release relay to bring about the operation of said magnet.
3. In an automatic switch, a line relay, a release relay, an operating magnet, a connection 40 between one pole of the exchange battery and one terminal of the operating magnet, a connection between the other terminal of the operating magnet and one terminal of the release relay, means for closing a circuit path between the other pole of the exchange battery and the other terminal of said release relay to operate said release relay, contacts 45 on the line relay for shunting the release relay to bring about the operation of said magnet, and a low-resistance control relay included in said shunt circuit.
4. In an automatic switch, an operating magnet and a release magnet, a release relay of relatively high resistance connected in series with the operating magnet, a change-over relay of relatively low resistance, means for periodically connecting said change-over relay in parallel with said high resistance relay, said operating magnet being inoperative in the first-mentioned circuit and operative in the second-mentioned circuit, and a circuit for said release magnet including normally-closed contacts of the said release relay and excluding the change-over relay.
5. In a telephone system wherein the release relay of an automatic switch is energized in series with the operating magnet of the switch and wherein a control relay is periodically connected in parallel with said release relay to effect operations of said operating magnet, a release magnet for said switch, and an operating circuit for said release magnet including contacts closed by the release relay upon deenergization and excluding said control relay.
6. In a selector, an impulse relay, a release relay, a contact pair on said impulse relay, a contact pair on said release relay, a current source, an operating magnet, and an operating circuit for said magnet including a connection from one pole of said source to the contact pair of said release relay and extending through said pair to said magnet by way of the contact pair of said impulse relay.
7. In a selector, a release relay and an operating magnet connected together, a line relay, a front contact on said line relay for closing a circuit through said release relay and magnet, and a back contact on said line relay for shunting said release relay.
8. In a selector, a release relay, an operating magnet, a line relay for closing a circuit through said release relay and magnet in series, said circuit including front contacts on said line relay which directly connect one side of the exchange battery to said release relay, and locking contacts on said release relay connected in parallel with said line relay contacts.
9. In a selector, a release relay, a magnet, and a grounded battery, all connected in series, a line relay for connecting ground to said release relay to energize the same, and a locking circuit for said release relay.
10. In a selector, a line relay, a release relay energized by said line relay, an operating magnet to which said line relay delivers ground impulses on deenergizing, and a circuit including contacts on said release relay for supplying ground to the armature of said line relay.
11. In a selector, an impulse relay, a release relay, an operating magnet, a current source, a connection from one pole of said source to one terminal of said magnet, the free terminal of said magnet and one terminal of said relay being connected together, and contacts on said impulse relay for connecting the other terminal of said release relay to the other terminal of said current source.
12. In a selector, a self-locking relay having a locking contact for connecting one pole of the exchange battery directly to one of its terminals, a connection from the other terminal of said relay to the other side of the exchange battery through an operating magnet of the selector, and contacts for periodically shunting said relay to operate said magnet.
13. In a selector, a self-locking relay hav-
